UNITED STATES PATENT OFFICE.

REINHOLD H. WAPPLER, OF NEW YORK, N. Y., ASSIGNOR TO WAPPLER ELECTRIC CONTROLLER COMPANY, OF NEW YORK, N. Y., A CORPORATION OF NEW YORK.

ENDOSCOPE.

No. 902,513.

Specification of Letters Patent.

Patented Oct. 27, 1908.

Application filed January 11, 1908. Serial No. 410,386.

To all whom it may concern:

Be it known that I, REINHOLD H. WAPPLER, a citizen of the United States, residing in the borough of Manhattan, city, county, and State of New York, have invented an Improvement in Endoscopes, of which the following is a specification.

Heretofore, endoscopes for use in making examinations for detecting and diagnosing urinary and kindred disorders, have usually comprised a lens tube and a sheath therefor, in the extremity of which latter a light bulb has been placed in an offset position,—for instance as shown and described in Letters Patent No. 702752 dated June 17th, 1902, and Letters Patent No. 723790 dated March 24th, 1903, both granted to me for improvements in endoscopes and other optical instruments,—wherein the light bulb 10 offset at the extremity of the sheath is nevertheless parallel therewith, and also as shown in my co-pending application Serial No. 364306, filed March 25th, 1907, for cystoscopes, in which the light bulb placed at 15 the extremity of the sheath is offset therefrom at an angle.

Now the object of my present invention is the provision of an endoscope in which a light bulb attachment is secured at the extremity of the endoscope and the instrument is so constructed that the parts of the light bulb attachment are separable and when these parts are separated, a sheath into which the lens tube of the instrument 20 fits, is removable, not only in order that this sheath may be removed but in order that when the instrument is inserted for the purpose of an examination, the lens tube thereof and its offset end containing the light 25 bulb attachment may be turned at the pleasure of the examiner without turning the sheath, which of course contacts with the walls of the organ through which the instrument is passed, thereby overcoming any liability of injury through tearing or otherwise to the said walls of the organs through 30 which the instrument is passed, and in carrying out my invention, I employ a tube and lenses therein, a sheath into which the 35 said tube fits and an electric light bulb attachment, the parts of which are separable and secured to the extremity of the said tube in an offset position and in such a manner that when the separable parts of the

light bulb attachment are separated, the 55 said sheath is removable.

In the drawing, Figure 1 is an elevation of the extremity of an endoscope made in accordance with my present invention, and Fig. 2 is a central longitudinal section and 60 partial elevation of the same.

Referring to the drawing, I employ a tube 10 in which a lens 11, together with other suitable lenses, are employed and the tube 10 is provided with an end piece 12 in which 65 and at a suitable inclination the reflecting lens 13 is set, all of which is similar to that shown and described in Letters Patent No. 723790, March 24th, 1903, aforesaid, and 14 is a sheath into which the lens tube 12 fits 70 and through which the same is adapted to pass. I also employ a socket member 15 which is approximately semi-spherical in outline, the outside diameter being equal to the outside diameter of the tube 10 and end 75 piece 12, the socket member 15 is interiorly screw threaded as shown at 16 and so is adapted to receive the screw threaded shank 17 of the tip member 18 in which an electric light bulb 19 is fitted, the socket member 15 80 and the tip member 18 comprising the electric light bulb attachment, the parts of which as will be apparent are separable.

Now in constructing the instrument, the socket member 15 is placed in any desired 85 position in the extremity of the lens tube or the end piece 12 thereof and is secured therein by being soldered thereto as indicated at 20 or otherwise, and as will also be apparent, the light bulb attachment may be placed at 90 any desired offset position and that when the tip member thereof is removed from the socket member 15, the sheath 14 will pass over the socket member 15, whereby the sheath 14 may be removed from the instrument. 95

I claim as my invention:

1. An endoscope comprising a tube, a lens therein, a sheath therefor and a light bulb attachment of separable parts secured to the 100 extremity of the said tube in such a manner that when the parts of the said attachment are separated, the said sheath is removable from the tube.
2. An endoscope comprising a tube, lens 105 therein, a sheath therefor, a socket member so shaped and secured in the end of the said tube as to permit the said sheath to pass over

- the socket member and so be withdrawn from the tube, and an electric light bulb tip adapted to be screwed into the said socket member.
- 5 3. An endoscope comprising a tube, lens therein, a sheath therefor, a semi-spherical socket member soldered in the end of the said tube in an offset position and an electric light bulb tip member adapted to be secured in the said socket member, the said socket member being so shaped and secured to the end of the tube that said sheath will pass over the said socket member and so be removable from the tube when the said light bulb tip is removed.
- 10 4. An endoscope comprising a tube, a lens therein, a sheath therefor, a socket member secured in the end of the said tube with its axis at an angle to the axis of the tube, the said socket member being so shaped that the 20 said sheath will pass over the same, and a light bulb attachment adapted to be secured in the socket member.
- 15 Signed by me this 28th day of December 1907.

REINHOLD H. WAPPLER.
